UNITED STATES PATENT OFFICE.

HENRY J. RICE, OF CINCINNATI, OHIO, ASSIGNOR TO HIMSELF, JOHN K. LOVE, JAMES S. SMITH, AND WILLIAM B. SMITH.

IMPROVEMENT IN GAS HAND-LAMPS.

Specification forming part of Letters Patent No. 117,331, dated July 25, 1871.

To all whom it may concern:

Be it known that I, HENRY J. RICE, of Cincinnati, in the county of Hamilton and State of Ohio, have invented certain Improvements in Gas Hand-Lamps; and I do hereby declare that the following, taken in connection with the drawing which accompanies and forms part of this specification, is a description of my invention, sufficient to enable those skilled in the art to practice it.

My improved lamp is a gas-generating one, expressly constructed with a view to giving a brilliant light from a broad gas-flame without the use of a chimney, and it is adapted for use for in-door as well as for out-door use, as in street-lamps, during cold as well as warm weather.

Figure 1 is an elevation, and Fig. 2 a vertical section of a lamp with my improvements thereon; Fig. 3, a top view of the wick-tube; and Fig. 4, a top view of the burner-tip.

A is the reservoir or vessel, of any convenient shape or material to contain a supply of any proper gas-generating fluid, such as gasoline. B is a wick-tube, passing through and closely connected with the cap C, the latter being arranged to be screwed or fitted tightly to place in the top opening of the reservoir, so as to make a perfectly air-tight joint, a rubber or other flexible ring or washer being preferably placed between the cap and the top of the vessel, the better to insure a tightness of the joint. The tube, while open at its bottom, is closed at its top, with the exception of a very minute and almost invisible orifice, 1, for the emission of the gas evolved to supply the flame, the gasoline, by capillary attraction of the wick 2, rising within the tube to a point a little below its top, the space between the top of the wick and the top of the tube forming a gas-chamber, as seen at 3. This space may be varied in dimension, as desired, according to the height of the wick. The wick-tube B I make of very thin metal, in order that the fluid or gasoline (which is of a very cold nature) shall, in passing up the wick, act as a non-conductor of heat. This is very essential, as it keeps the lamp from becoming heated, and this prevents liability to explosions. D is a taper screw-plug. E is a copper tube, of a size to fit snugly over the wick-tube and hold its position thereon by friction at any desired elevation. F F are copper lips or flat wings surmounting tube E, and between these two wings is located a lava tip

or burner, G, having a vertical slit in its top, the same fitting into the top of tube E, as seen in the drawing. This tip lodges in the tube and the copper lips rise a little above it, so as to permit only the lower edge of the flame to come in contact with them. The slit in the burner I place parallel with the general direction of the sides of the wings F, the latter at their outer ends approaching each other somewhat as seen in Fig. 4. A space, 4 4, is left for the descent of atmospheric air between the lava burner and the copper tips, in order to cause complete combustion of the gas, thereby dispensing with the use of a chimney, which in my construction, is not needed. One method which I employ to give these descending currents is to have a ring of small perforations made in the wing or bonnet just between the lava tip and the outer wall of the copper tube or bonnet, these perforations surrounding the lava tip. These fine descending currents of atmospheric air outside the lava tip, which are caused by the suction created by the rapid ascent of heated gas through this tip, commingle with the mixed air and gas passing from orifice 1 and openings 5 5, and strengthen the force of current as they all together merge into one united stream and pass up through the lava tip. The effect is that, when the lamp is lighted, the combustion is so perfect that a clear transparent space, as seen at 6, is perceived between the top of the lava tip and the lower visible edge of the flame. The amount of atmospheric air entering at the side openings 5 5 in the tube E may be regulated, as required, according to circumstances or the state of the weather; or for in-door or out-door uses by simply raising or lowering the tube. By reason of having the gasoline closely confined and with no outlet except through the minute orifice 1 located high above the liquid, a pressure is exerted upon the gas generated, which, when the brass tube is slightly warmed by grasping it for a moment by the hand, when the lamp is a little further heated at the top, is increased, so that a jet is forced out of the orifice 1, and which passes directly upward into and through the lava burner, the air at the same time passing down the perforations or passages 4 4 around and outside the burner, resulting in a spread, broad, brilliant flame.

The pressure, it will be seen, is not derived from the weight of the mass of fluid descending from above by gravity, as is usually the practice; but

from the expansive upward pressure. In order to cause my lamp to burn, I exclude the air from the reservoir and keep the plug D tight, and only admit air when the lamp is extinguished, to prevent its otherwise overflowing. Only when the lamp is being filled do I loosen the cap C. One great value incident to this close confinement in an air-tight vessel is that, when accidentally upset, the liquid cannot run out and take fire. It is well known that the effect of flame on copper, if the upper portion of the flame is permitted to come in contact with it, is to give the light a greenish cast, thus diminishing, to a great extent, its brilliancy. It is also well known that brass causes the light to be more brilliant; but brass, however, soon burns and breaks off, while copper lasts at least seven times as long; besides, it heats much quicker and holds its heat much longer.

Now, by my construction of the adjustable copper tip and wings, with a lava tip placed inside the same, and with a descending air-current between them, and the lowest points only of the flame, if any, coming in contact with the wings, yet with the commingling of the air and gas, as described, at the bottom of the lava tip, and also between such bottom and the tube E, at a point below the copper wings, I am enabled to obtain

more heat than is required, resulting in the saving of at least five hundred per cent. in light, tips, &c. When my lamp is placed in a street-lamp post, it requires more heat on cold nights. To supply this, I simply place the lava tip G higher, and thereby admit more air to pass down and up, as explained before, thereby creating greater combustion, and three times the amount of heat, if required, so that it will make gas out of doors the coldest nights, and without ever going out. The side holes in the tube E may, if desired, be dispensed with by my construction, and in such case the atmospheric air would be conveyed to the bottom of the lava tip only by means of the above-named descending currents.

I claim—

In combination with an air-tight reservoir and wick-tube B rising above it, and constructed as described, the adjustable copper tube E, surrounded by a lava burner and copper wings or bonnet F F, and provided with air-inlets and passages for descending currents, all as shown and described.

HENRY J. RICE.
